(57) **CLAIM**

The ornamental design for an electronic smoking article charger, as shown and described.

DESCRIPTION

FIG. 1 is a front elevational view of an electronic smoking article charger showing our new design in a closed orientation, the rear view being a mirror image thereof.

FIG. 2 is a top plan view thereof, the bottom view being a mirror image thereof.

FIG. 3 is left side elevational view thereof.

FIG. 4 is a right side elevational view thereof; and,

FIG. 5 is a perspective view of the electronic smoking article charger shown in FIG. 1 in an open orientation.

The broken lines shown in FIGS. 3, 4 and 5 are included for the purpose of illustrating unclaimed portions of the electronic smoking article charger and form no part of the claimed design.

The claimed design is not limited to the surface finish shown on the electronic smoking article charger in the photographs.

1 Claim, 3 Drawing Sheets
